UNITED STATES PATENT OFFICE

FREDERICK J. OSIUS AND MAURICE SEIDERMAN, OF MIAMI, FLORIDA; SAID SEIDERMAN
ASSIGNOR TO SAID OSIUS

DESIGN FOR A DRINK MIXER

Application filed September 27, 1932. Serial No. 45,086. Term of patent 14 years.

To all whom it may concern:

Be it known, that we, FREDERICK J. OSIUS and MAURICE SEIDERMAN, a citizen of the United States and a subject of Russia, respectively, residing at Miami, in the county of Dade and State of Florida, have invented new, original, and ornamental Design for Drink Mixers, of which the following is a description, reference being had to the accompanying drawing, forming part thereof.

In the drawing,

Fig. 1 is a full front elevation of the drink mixer showing our new design; and
Fig. 2 is a top view thereof.

We claim:

The ornamental design for a drink mixer, as shown.

FREDERICK J. OSIUS.
MAURICE SEIDERMAN.
